UNITED STATES PATENT OFFICE.

GEORGE C. VARWIG, OF PHILADELPHIA, PENNSYLVANIA.

DESIGN FOR A TOILET-CASE.

SPECIFICATION forming part of Design No. 18,242, dated April 3, 1888.

Application filed February 27, 1886. Serial No. 265,521. Term of patent 3½ years.

To all whom it may concern:

Be it known that I, GEORGE C. VARWIG, a citizen of the United States, residing in the city and county of Philadelphia, State of Pennsylvania, have invented and produced a new and original Design for Toilet or other Cases, of which the following is a specification, reference being had to the accompanying photograph, forming part thereof.

10 The leading features of my design for a toilet or other case are the lid, body, and base thereof of the form of a leaf.

15 A represents a perspective view of a box or toilet case, as seen from the front thereof, embodying the features of my invention, said case consisting of the lid 1, body 2, and base 3, said parts being of the form of a leaf in horizontal section. The upper face of the lid is convex, and has on its face within the edge a 20 border, 4, leaving a well-defined rim or bead,

5. The base 3 is wider than the body and forms a broad rim or bead, 6, at the bottom thereof outside of the body portion. The lid has veins 7 and a stem, 8.

I claim—

25 1. The design for a toilet-case, consisting of a lid, a body, and a base, each of which is of the form of a leaf, and the base having a rim or border outside of said body portion, substantially as shown and described.

30 2. In a design for a toilet-case, consisting of a lid, a body, and a base of the form of a leaf, the lid having a border, 4, its main portion being convex, substantially as shown and described.

GEO. C. VARWIG.
